232,901

INSULATED BOTTLE WITH ATTACHED CUP

Vernon D. Bell, Westerly, R.I., and Charles L. Seltz,
Ann Arbor, Mich., assignors to King-Seeley Thermos
Co.

Filed Apr. 20, 1973, Ser. No. 352,943

Term of patent 14 years

Int. Cl. D7—01

U.S. Cl. D7—77

FIG. 1 is a top perspective view of an insulated bottle with attached cup showing our new design;

FIG. 2 is a front elevational view;

FIG. 3 is a side elevational view;

FIG. 4 is a top plan view;

FIG. 5 is a bottom plan view.

We claim:

The ornamental design for an insulated bottle with attached cup, substantially as shown and described.
